[57] CLAIM

The ornamental design for a computer stand with slideable shelf and document holder, as shown and described.

DESCRIPTION

FIG. 1 is a perspective view of a computer stand with slideable shelf and document holder showing my new design;

FIG. 2 is a perspective view with the shelf in extended position and the document holder in upright position;

FIG. 3 is a top plan view of FIG. 1;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view of FIG. 2 with the document holder in an alternate position of use;

FIG. 9 is a bottom plan view thereof;

FIG. 10 is a front elevational view thereof;

FIG. 11 is a left side elevational view thereof;

FIG. 12 is a front elevational view, the broken line showing of a computer and keyboard is for illustrative purposes only; and

FIG. 13 is a rear elevational view thereof.
